UNITED STATES PATENT OFFICE.

TONY TRIMBOLI, OF UHRICHSVILLE, OHIO.

DESIGN FOR A RUBBER HEEL.

57,874.

Specification for Design.

Patented May 10, 1921.

Application filed April 8, 1920. Serial No. 372,370. Term of patent 7 years.

To all whom it may concern:

Be it known that I, TONY TRIMBOLI, a subject of the King of Italy, residing at Uhrichsville, in the county of Tuscarawas and State of Ohio, have invented a new, original, and ornamental Design for Rubber Heels, of which the following is a specification, reference being had to the accompanying drawing, forming part thereof.

The figure is a view in perspective of a rubber heel, showing my new design.

I claim:

The ornamental design for a rubber heel, as shown.

TONY TRIMBOLI.
